(57) **CLAIM**

The ornamental design for a stabilization device, as shown and described.

DESCRIPTION

FIG. 1 is a perspective view of the stabilization device. FIG. 2 is a left elevational view of the stabilization device. FIG. 3 is a right elevational view of the stabilization device. FIG. 4 is a back view of the stabilization device.

FIG. 5 is a front view of the stabilization device.

FIG. 6 is a top view of the stabilization device.

FIG. 7 is a bottom view of the stabilization device.

FIG. 8 is a perspective view of the stabilization device in combination with a monitor mounting bracket; and, FIG. 9 is a perspective view of the stabilization device in combination with a monitor mounting bracket and a monitor.

The features shown in broken lines in the Figures form no part of the claimed design.
